CLAIM

The ornamental design for a necklace or similar article, as shown and described.

DESCRIPTION

FIG. 1 is a top perspective view of a necklace or similar article showing my new design;

FIG. 2 is a bottom perspective view thereof;

FIG. 3 is a top perspective view of a necklace or similar article showing a modified form of my new design as a bracelet;

FIG. 4 is a bottom perspective view thereof; and

FIG. 5 is an enlarged scale fragmentary perspective view of the beaded portion in expanded condition.

The broken line showing of indicia in FIGS. 1 and 3 is for illustrative purposes only and forms no part of the claimed design.
